UNITED STATES PATENT OFFICE.

JOHN J. DU BOIS, OF PUEBLO, COLORADO, ASSIGNOR TO THE DU BOIS NOISELESS CROSSING COMPANY, OF PUEBLO, COLORADO, A CORPORATION OF COLORADO.

RAILWAY CROSSING.

Application filed November 14, 1923. Serial No. 674,699.

To all whom it may concern:

Be it known that I, JOHN J. DU BOIS, a citizen of the United States, residing at Pueblo, in the county of Pueblo and State 5 of Colorado, have invented certain new and useful Improvements in Railway Crossings, of which the following is a specification.

My invention relates to a railway crossing, and the main object of the invention 10 is to provide a crossing that will give more service than ordinary ones and which does not require replacement and tightening of bolts as is generally the case with similar 15 devices. One advantage of this construction is that it is noiseless because the rails are joined very firmly to the crossing, presenting no sharp edges against the wheels and, furthermore, on account of no bolts 20 being provided that may be loosened by the vibration of passing trains.

Another object of the invention is to make 25 the crossing very firm by mounting it on a concrete block with cast-in anchor hooks. This tends to make a great saving in repairs, particularly as no ties are used under the crossing.

Another advantage of this construction 30 is that there are no parts to get out of order or break as the crossing forms a single unit. A train can pass the crossing at a rate of speed up to seventy miles per hour without 35 being derailed and this railway crossing will outlast ordinary ones by from four to six years, the life of the present crossings being only two to four years.

Water tending to very rapidly deteriorate 40 iron constructions will not affect this railway crossing as it is laid on a concrete slab instead of coming in contact with the soil.

In the accompanying drawings, one embodiment of the invention is illustrated, and—

Figure 1 is a top plan view partly in section of this railway crossing;

Figure 2 is a section along line 2—2 of Figure 1;

Figure 3 is a fragmentary perspective view of one end of the railway crossing, and

Figure 4 is a section along line 4—4 of Figure 2.

The railway crossing consists of four intersecting members or bars 10 cast together to form a unit or block of malleable steel.

These bars have preferably a trapezoidal 55 cross section with upwardly slanting sides 11 and 12 making the base somewhat wider than the top of the bar. These bars intersect, as indicated in Figure 1, at right angles, but it is evident that any other angle may 60 be selected to suit conditions. The bars are provided with channels 13 in their top faces slightly less in depth than the height of the wheel flange. This depth extends between the intersections of the tracks or a little 65 beyond. The bottom of the channels at each end thereof is then inclined downwardly to a depth greater than the height of the wheel flange as shown at 27 in the drawings. The inner face 9 of the outer wall 14 along the 70 channels makes contact with the wheels, while the inner wall 15 is the guard. The ends of each inner wall 15 are preferably tapered, as indicated at 16, to guide the 75 wheel flanges into the channels 13.

The inner side of the end of each outer wall 14 is recessed to accommodate the rail head 17, the web 18 and the foot 19, as best seen in Figure 4, so that when the rails are assembled to the crossing the inner face 20 80 of the rail head is alined with the corresponding face 9 of the channel 13, see also Figure 1. The heavier middle portion 21 of the recess wall is provided with a set of studs 22 securely held in the bar. These 85 studs are intended to enter suitable apertures 23 in the web 18 of the rail and to be riveted over to firmly connect the rail with the bar. In addition to these riveted studs the joint 26 between the rail and the bar is 90 preferably welded.

Instead of using ties for the railway crossing, I preferably provide a heavy slab of concrete 24 upon which the railway crossing 95 is placed and into which are cast hooks 25 adapted to engage in corresponding sockets furnished in the railway crossing at each intersection of the bars 10, but it is evident that additional hooks may be provided to engage the under sides of the bars, if thought 100 necessary.

The railway crossing shown in the drawings is constructed for standard gage track which is four feet eight and one-half inches in width, but it is evident that for narrow 105 gage track the crossing will be made to suit the same.

With the railway crossing placed on the

concrete slab and connected therewith by means of anchor hooks 25 no displacement horizontally in any direction is possible and the crossing can accordingly resist the largest 5 and heaviest locomotives. The bars may be extended if necessary where traffic is particularly heavy so that more anchor hooks may be furnished to retain the railway crossing in position.

10 When a train approaches the crossing the car wheels run with their broad faces on top of the rails, as indicated at 28 in Figure 2 of the drawings. Soon after entering the crossing block they encounter the rising bottoms 15 27 of the channels which, by contacting with the outer peripheries of the wheel flanges, cause the wheels to be lifted bodily from the top surfaces of the walls 14 as seen at 29 in Figure 2. The wheels will thus be 20 made to roll on their flanges along the bottom of the channels over the crossing block and finally be let down again on the top of the rails at the exit end of the crossing block. All knocking at the intersections is in this 25 manner completely prevented.

Having thus described the invention, what is claimed as new is:

1. In a railway crossing having intersecting bars provided with channels on the top 30 side thereof, a recess formed at each end of the bars adapted to receive the end of a rail, means for securely joining a rail end to the corresponding end of each of said bars, said means including studs in said recess adapted 35 to engage in corresponding apertures in the rail end, the adjacent faces of the rail end and the bar end being welded; a concrete slab constituting the base for said intersecting bars, and anchor hooks cast in said con-

crete slab adapted to engage with corresponding sockets in said intersecting bars. 40

2. In a railway crossing having intersecting bars of trapezoidal cross section, said bars being provided with channels on the top side thereof, a recess formed at each end of 45 these bars adapted to receive the end of a rail, and means for securely joining a rail end to the corresponding end of each of these bars, said means including studs in said recess adapted to engage in corresponding 50 apertures in the rail end, said studs being riveted to the rail end, and the adjacent faces of the rail end and the bar end being welded, the wall of said channel opposite said recess being tapered to form a guide for the 55 wheel flange.

3. In a railway crossing having intersecting bars of trapezoidal cross section, said bars being provided with channels on the top side thereof, a recess formed at each end 60 of these bars adapted to receive the end of a rail, and means for securely joining a rail end to the corresponding end of each of these bars, said means including studs in said recess adapted to engage in corresponding 65 apertures in the rail end, said studs being riveted to the rail end, and the adjacent faces of the rail end and the bar end being welded, the wall of said channel opposite said recess being tapered to form a guide for the 70 wheel flange; a concrete slab constituting the base of the railway crossing, and anchor hooks cast in said concrete slab adapted to engage with corresponding sockets in said intersecting bars. 75

In testimony whereof I affix my signature.

JOHN J. DU BOIS. [L. s.]
